Primary Examiner — Jonathan J Han

(57) **CLAIM**

The ornamental design of a shoe, as shown and described.

DESCRIPTION

FIG. 1 is a first side perspective view of a shoe;

FIG. 2 is a second side perspective view thereof;

FIG. 3 is a first side view thereof;

FIG. 4 is a rear view thereof; and,

FIG. 5 is a second side view thereof.

The broken lines showing the remainder of the shoe are for environmental purposes only, and form no part of the claimed design.
